Primary Examiner — Mark Goodwin*(74) Attorney, Agent, or Firm* — Lorenz & Kopf, LLP(57) **CLAIM**

The ornamental design for a work vehicle body panel, as shown and described.

DESCRIPTION

FIG. 1 is a top, front, right perspective view of a work vehicle body panel showing our new design with exemplary work vehicle environment;

FIG. 2 is a top, front, right perspective view thereof;

FIG. 3 is a right side elevational view thereof;

FIG. 4 is a left side elevational view thereof;

FIG. 5 is a front end view thereof;

FIG. 6 is a rear end view thereof;

FIG. 7 is a top plan view thereof; and,

FIG. 8 is a bottom plan view thereof.

The broken line showing of a work vehicle in FIG. 1 and the hood portions in FIGS. 1-8 is included for the purpose of illustrating environmental structure only and forms no part of the claimed design.

The nature of this product is an exterior body for a vehicle, such as a work vehicle used in the construction and forestry industries, for example a hood for a backhoe.
